APPLICATOR

Arne Habostad, Fairbanks, Alaska

Application February 18, 1944, Serial No. 522,996

1 Claim. (Cl. 132—13)

My invention relates to improvements in applicators for use on hair tonic bottles to apply tonic therefrom to the hair and scalp.

The primary object of my invention is to provide a simply constructed, inexpensive device which may be easily and quickly attached to hair tonic bottles having threaded necks and which is operative to distribute said tonics, particularly heavy oil tonics, over the scalp and around the roots of the hair without necessitating rubbing with the fingers, and which obviates getting oil on the hands, waste of oil, and saves time and labor in applying hair tonics and the like.

Other and subordinate objects are also comprehended by my invention, all of which, together with the precise nature of my improvements, will be readily understood when the succeeding description and claims are read with reference to the drawings accompanying and forming part of the specification.

In said drawings:

Figure 1 is a view in front elevation of my improved applicator in its preferred embodiment.

Figure 2 is a view in side elevation.

Figure 3 is a view in horizontal section taken on the line 3—3 of Figure 1 and drawn to an enlarged scale,

Figure 4 is a detail view in vertical section taken on the line 4—4 of Figure 1 and drawn to an enlarged scale, and

Figure 5 is a view partly in elevation and partly in section of an adapter forming part of my invention.

Referring to the drawings by numerals, according to my invention, in the preferred embodiment thereof, a comb-like member is provided comprising a flat, elongated body 1 provided at its bottom with a coplanar row of teeth 2, and a central neck at its top terminating in an internally threaded collar 4 for screwing onto the externally threaded neck 5 of a hair tonic bottle 6.

The teeth 2 taper, outwardly of the body 1, and are provided on one side with tips 7 rounded, as at 8. An axial duct 9 is provided in the neck 3. A relatively smaller diameter duct 10 extends from the inner end of the duct 9 in the body 1 obliquely of the duct 9 toward one end of the body 1. A second duct 11, similar to duct 10, extends from an intermediate point in the duct 10 obliquely toward the opposite end of the body 1. The outer ends of the ducts 10, 11 terminate in lateral branch ducts 12 extending through the outermost, or end, teeth 2 of the row and which are provided with tapered restricted

outlet ends 13 opening onto the rounded tips 8 of said teeth. Lateral branch ducts 14, similar to ducts 12, extend from the ducts 10, 11 to the remaining teeth 2 with outlet ends 15 arranged similarly to the outlet ends 13. The outlet ends 13, 15 are offset inwardly from the terminals, or tips, of the teeth 2 to prevent the same from becoming clogged by dirt, dandruff, et cetera, accumulated on the scalp. The terminals, or tips, 7 of the teeth 2 are arranged in an arc generally conforming to the shape of the average head.

A threaded needle valve member 16 extends into the neck 3 and the inner end of the duct 9 on one side of the neck for closing said duct.

On the other side of said neck 3, of the applicator, is a valved air inlet pump comprising a tubular air inlet nozzle 17 fitted into and secured in the neck 3 to extend radially therefrom with the inner end thereof opening into the duct 9 and internally beveled to provide a valve seat 18. A resilient bulb 19 of rubber or the like is attached to the outer end of said nozzle 17 by means of a nipple portion 20 internally grooved, as at 21, the interfit with a pair of external flanges 22 on the outer end of the nozzle 17. A relatively smaller diameter valve stem 23 extends through the nozzle 17 with a flaring valve member 23' on the inner end thereof for engagement with the valve seat 18, and is provided with an operating button 24 on its outer end within the bulb 19. A coil spring 25 circumscribed on the valve stem 23 between the button 24 and the outer end of the stem 17 urges said stem outwardly of the nozzle 17 and normally engages the valve member 23' with the seat 18. An air inlet aperture 26 is provided in the bulb 19 in the axis of the button 24 and stem 23.

Adapters, such as shown at 27 in Figure 5, may be provided for screwing into the collar 4 and onto bottle necks of larger sizes than the internal size of the collar 4.

The described applicator may be constructed, with the exception of the needle valve member 16 and the air pump, of plastic or any other light, strong, inexpensive material.

Referring now to the use and operation of my invention, with the applicator attached, as described, and the needle valve member 16 opened, as occasion may require, the bottle 6 is held with one hand, upside down, by the neck 5, and the bulb 19 compressed, as by the index finger, with the finger closing the aperture 26, until the finger engages the button 24 and presses the same sufficiently to unseat the valve member 23' and open the air nozzle 17 to the duct 10. Air in the bulb

19 is thus forced into the duct 9 and the contents of the bottle 6 so that said contents may flow freely out of the teeth 2 by way of the ducts 12, 14. With the bottle 6 and body 1 held substantially upright, the tips 1 of the teeth 2 are rubbed over the scalp, the bulb 19 being released and again compressed, in the manner described, to admit more air as may be necessary to attain the desired flow of the contents of the bottle out of said teeth 2. By adjusting the needle valve member 16, the discharge from the ducts 12, 14, or in other words, the teeth 2, may also be varied according to the type of hair tonic being used, that is, heavy or light oil.

The button 24 is spaced from the outer end 15 of the nozzle 17, normally, so that it engages said end of the nozzle when the valve member 23' has opened sufficiently, and thereby prevents further opening movement of said member.

The foregoing will, it is believed, suffice to impart a clear understanding of my invention without further explanation.

Manifestly, the invention, as described, is sus-

ceptible of modification without departing from the inventive concept, and right is herein reserved to such modifications as fall within the scope of the appended claim.

What I claim is:

An applicator for attachment to a bottle having a threaded neck comprising an elongated body adapted to extend crosswise of the mouth of the bottle, an internally threaded attaching neck extending centrally from one side of the body for turning onto the neck of the bottle, and provided with an axial bore extending into said body, a row of teeth extending from the other side of said body, ducts extending into said teeth and in communication with the first-mentioned duct, the ducts in the teeth opening onto the sides of the teeth adjacent the tips thereof, and manipulative means to introduce air under pressure into the duct first mentioned including a valved compressible bulb, the valve of said bulb comprising a push button within the bulb operative by compression of the bulb against the same to open said valve.

ARNE HABOSTAD.
